BAR OF SOAP OR SIMILAR ARTICLE

Emil V. Bonardi, Cliffside Park, N.J., assignor to Lever Brothers Company, New York, N.Y., a corporation of Maine

Filed Sept. 4, 1964, Ser. No. 81,598

Term of patent 14 years

(Cl. D73—1)

FIG. 2

FIG. 3

FIG. 5

FIG. 4

FIG. 1 is a top plan view of a bar of soap, showing my new design, the bottom thereof being similar in appearance;

FIG. 2 is a side elevational view thereof, the opposite side being similar in appearance;

FIG. 3 is an elevational view of the bar of soap as seen from the angle indicated by the arrows 3—3 shown in FIG. 1;

FIG. 4 is an elevational view of the bar of soap as seen from the angle indicated by the arrows 4—4 shown in FIG. 1; and

FIG. 5 is an end elevational view thereof, the opposite end being similar in appearance.

I claim:

The ornamental design for a bar of soap or similar article, substantially as shown and described.
